RAZOR BLADE CRUSHER

John F. Sheahan, Scottdale, Pa.

Application November 18, 1939, Serial No. 305,201

4 Claims. (Cl. 29—66)

This invention relates to a razor blade crusher.

An object of the invention is the provision of a device having a housing provided with an opening through which the blades are inserted with the blades falling between a pair of jaws and supported thereby until means is operated for moving one of the jaws towards the other jaw for crushing the blades into small pieces so that after the jaws are released and separated the particles will fall into a container located beneath the crushing jaws.

A further object of the invention is the provision of a device for crushing razor blades between a pair of jaws, one of the jaws being fixed in position while the other jaw is moved into cooperative relation with the fixed jaw with means for causing the movable jaw to contact the fixed jaw, a support for maintaining the blade between the jaws forming guides for the movable jaw, means also being employed for preventing lateral displacement of the blade when resting upon the guides, said movable jaw adapted to be forced into engagement with the fixed jaw.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in elevation partly in section of a blade crushing device.

Figure 2 is a horizontal section taken along the line 2—2 of Fig. 1.

Figure 3 is a transverse vertical section taken along the line 3—3 of Fig. 1, and

Figure 4 is a fragmentary vertical section taken along the line 4—4 of Fig. 1.

Referring more particularly to the drawing, 10 designates generally a frame which is composed of a vertically disposed plate 11, a laterally projecting cylinder 12, internally threaded bosses 13, 14 and pairs of horizontally disposed guide rods 15 and 16.

The periphery of the plate 11 is provided with a groove 20 adapted to receive the free end of a cup-shaped cover, generally designated by the numeral 21.

A vertical wall 22 of the cover is provided with passages 23-24 to receive, respectively, the guide rods 15 and 16. The outer projecting ends of these rods are threaded, as shown at 25 and 26,

respectively, to receive nuts 27 for securing the cover tight against the plate 11. The inner ends of these rods 15 and 16 are also threaded, as shown at 28 and 29, respectively, and screwed into the internally threaded bosses 13 and 14, 5 respectively.

A jaw 30 is secured to the inner face of the plate 22 of the cover 21 and is provided with teeth 31 formed complementarily to the teeth 32 formed on a movable jaw 33 which has passages 35 to receive, respectively, pairs of spaced guide rods 15 and 16. These passages are formed in ears 36 and 37.

It will be noted from Fig. 3 that the ears 37 are closer together than the ears 36 and the space 15 between the guide rods 16 is less than the width of a blade so that when a blade is inserted through an opening 40 formed in the top 41 of the cover 21, the lower end of the blade will rest upon the rods 16 and be supported between the 20 jaws 30 and 33.

A pair of plates 42 project laterally in vertical planes from the inner face of the side wall 22 of the cover 21 and are in close association with the opposite ends of the jaws 30 and 33 in order to 25 prevent the blade after it has been dropped through the openings 40 and after it has rested on the rod 16 from falling laterally and away from the cooperating jaws.

The plunger 45 is slidably mounted within the 30 cylinder 12 and has a portion cut away, as shown at 46, to provide a rack 47. The outer end of the plunger, as shown at 48, is retained to form a closure for the outer open end of the cylinder 12. A pinion or toothed wheel 50 is formed on one 35 end of a shaft 51. The pinion is mounted in bearings 52 formed in the side walls of the cylinder 12.

The shaft 51 extends through an opening 53 in a side wall 54 of the cup-shaped cover 21 and is provided with a crank arm 55 which when rocked will rotate the pinion in one direction. A coil spring 56 embraces the shaft 51 and has one end, as shown at 57, secured to one of the guide rods 15. The other end of the spring, as shown at 58, engages over the lever or arm 55. Thus it will be seen that when the lever is moved in the direction indicated by the arrow in Fig. 1, pinion 50 will be revolved in one direction while when the lever is released the coil spring will 50 return the lever to its inoperative position.

A pair of ears 60 project laterally from the back of the jaw 33 and are provided with perforations 61 to receive a pin 63. This pin has a head 63 which rests upon the upper ear 60. The pin 55

is inserted through a passage 65 formed in the plunger 45 so that when the plunger 45 is reciprocated it will move the jaw 33. The pin 62 in connection with the ears 60 and the passages 65 in the plunger 45 maintains the jaws 33 in vertical alignment with the fixed jaw 30. In this connection, however, the inner end of the plunger 45 merely abuts the rear face of the jaw 33. On the other hand, the inner end of the plunger 10 may be rigidly secured to the rear face of the fixed jaw.

The wall 22 of the cover 21 is provided with an opening 66 through which is slid a drawer or receptacle 67 with the bottom of the drawer resting upon the bottom of the cover 21. A manipulating knob 68 is secured to the front wall 69 of the drawer 67 so that the drawer may be withdrawn periodically to remove the broken blades therefrom.

20 The operation of my device is as follows: With the drawer 67 in place and the jaw 33 automatically moved away from the fixed jaw 30 by means of the spring 56, the parts are in position to receive a blade which is adapted to be crushed between the jaws. The blade is then slipped through the opening 40 in the top 41 of the cover 21 and it will fall downwardly and the lower end of the blade will rest upon the guide rods 16. The laterally projecting spaced plates 42 at the opposite ends of the jaws 30 and 33 will also not only guide the blade to a position directly between the jaws but said plates will also maintain the blade in position.

25 The arm or lever 55 is then moved in the direction indicated by the arrow shown in Fig. 1 whence the pinion 59 will be rotated and since it is in mesh with the teeth of the rack 47, the plunger 45 will be moved towards the right in Fig. 1 and thereby force the jaw 33 towards the jaw 30. When the lever has been moved through a sufficient angle the teeth 31 and 32, respectively, of the jaws 30 and 33 will crush the blade into small pieces. At this time the cooperating teeth 70 and 71 of the jaw 30 and the teeth 72 30 at the jaw 33 will be cooperatively engaged for closing the opening 40, thereby preventing dust and fine particles from being discharged from the housing or cover 21.

35 When the arm 55 is released the coil spring 56 which has been wound tight by the movement of the arm 55 will return the arm to its normal cooperative position, as shown in Fig. 1, and the particles from the crushed blades will then fall by gravity into the receptacle or drawer 67. The device is now in position to crush another blade.

40 The device may be of the portable type or it can be so constructed that it may be fixed in position on any suitable support.

45 I claim:

50 1. A razor blade crusher comprising a housing

5 provided with a slot for the insertion of razor blades to be crushed, a jaw fixed within the housing, a second jaw movable into engagement with the fixed jaw, means slidably mounting the second jaw, means moving the second jaw into 5 and out of engagement with the fixed jaw for causing the second jaw to close the slot when the blade is being crushed.

2. A razor blade crusher comprising a housing, a jaw fixed within the housing, a second jaw 10 adapted to be moved into engagement with the fixed jaw, ears projecting from the second jaw and provided with passages, rods fixed within the housing and received by the passages for slidably mounting the second jaw, a rack secured to the 15 second jaw, a toothed wheel meshing with the rack, means rotating the wheel in one direction for moving the jaw, a spring reversely rotating said wheel and returning the second jaw to an inoperative position, the housing having an 20 opening for the insertion of blades, the jaws closing the opening when a blade is being crushed.

3. A razor blade crusher comprising a frame including a vertically disposed plate and guide 25 rods projecting from said plate, a plunger slidably mounted in the cylinder and provided with a rack, a movable jaw connected with the rack and slidably mounted on the rods, a cover housing the frame and secured thereto, a jaw fixed to 30 the inside of the cover in alignment with the movable jaw, a pinion in mesh with the rack, means rotating the pinion to cause the rack to force the movable jaw into engagement with the fixed jaw, and means reversely rotating the pinion 35 for returning the movable jaw to an inoperative position.

4. A razor blade crusher comprising a frame including a vertically disposed plate and guide rods projecting from said plate, a plunger slidably mounted in the cylinder and provided with a rack, a movable jaw connected with the rack and slidably mounted on the rods, a cover housing the frame and secured thereto, a jaw fixed 40 to the inside of the cover in alignment with the movable jaw, a pinion in mesh with the rack, means rotating the pinion to cause the rack to force the movable jaw into engagement with the fixed jaw, means reversely rotating the pinion 45 for returning the movable jaw to an inoperative position, said guide rods projecting exteriorly of the cover, means cooperating with the projecting ends of the guide rod for securing the cover in position, and guide plates projecting 50 from the cover and embracing opposite edges of the jaws for maintaining a blade in position between the jaws.

JOHN F. SHEAHAN.
